UNITED STATES PATENT OFFICE.

FREDERICK M. FURBER, OF REVERE, MASSACHUSETTS, ASSIGNOR TO UNITED SHOE MACHINERY COMPANY, OF PATERSON, NEW JERSEY, A CORPORATION OF NEW JERSEY.

SPLITTING-MACHINE.

1,111,255.

Specification of Letters Patent. Patented Sept. 22, 1914.

Application filed December 2, 1908. Serial No. 435,623.

To all whom it may concern:

Be it known that I, FREDERICK M. FURBER, a citizen of the United States, residing at Revere, in the county of Suffolk and Commonwealth of Massachusetts, have invented certain Improvements in Splitting-Machines, of which the following description, in connection with the accompanying drawings, is a specification, like reference characters on the drawings indicating like parts in the several figures.

This invention relates to machines for splitting stock and is shown as embodied in a machine which is especially adapted for splitting a died out piece of leather.

One object of this invention is the provision, in a machine of the above class, of means for causing the knife to split from the stock a sheet or shaving, or a flap, of uniform thickness. In the machine illustrated this result is obtained by providing a gage to bear upon the surface of the stock in advance of the point at which it is engaged by the knife, the distance between the lower or effective edge of said gage and the plane of the cutting edge of the knife remaining constant and corresponding to the thickness of the flap or of the piece split off. Preferably also, means may be provided to adjust the machine so as to change the distance between the effective edges of the gage and knife and consequently to vary the thickness of the flap or the piece split off.

Another object of this invention is the provision of means for causing a flap which has been produced on the stock to be removed therefrom when desired. In one embodiment of the invention this result may be accomplished by providing means which becomes operative when the knife has cut for a certain distance to automatically cause said knife to leave the stock, thereby splitting from the stock a piece of uniform thickness which may have one edge beveled. To produce this bevel the means above referred to may be adapted to change automatically the distance between the effective edges of the gage and knife, thereby causing said knife to cut a piece which is progressively thinner from the time at which said means becomes operative until the knife leaves the stock. In another embodiment of this invention the means for causing the flap which has been produced on the stock to be removed therefrom may take the form of a

second knife, and this knife may conveniently be caused to operate on the return stroke of the common knife carrying member. Preferably this second knife is adjustable on its support so that the angle of the bevel produced on one edge of the shaving may be varied within wide limits, these limits being wide enough to allow the knife to operate in a direction at right angles to the plane of the surface of the shaving if desired.

It is advantageous to provide means for varying the point at which this flap removing means becomes operative. This means may be any suitable one, and in the illustrated embodiments of the invention three separate forms are shown. In the first form the member which depresses the gage is a wiper or cam of any given form so attached to its support that other wipers of any desired contour may be substituted. In the second form the member which depresses the gage is adjustable so as to vary the point at which said gage becomes operative. In the third form the member which carries the second knife is adjustable as is also the abutment which causes said knife to engage the stock. Attention is directed to the fact that, although these various means for causing the flap to be removed from the stock and for varying the point at which said means becomes operative are quite distinct in their form and manner of operation, nevertheless they serve to accomplish identical purposes and that obviously other forms may be substituted without departing from the scope of this invention.

In machines of the class described, it is advantageous to provide means for determining the extent of the split produced in the stock. This may be accomplished by providing means for varying the extent of the effective stroke of said knife; and said means may be of any suitable form, that shown in the illustrated embodiment being adapted to vary the initial position of the knife. Heretofore it has been customary to provide an adjustable stop or guide against which to place the edge of the stock, the position of the guide determining the extent of the cut. However, owing, among other things, to the small available space between the knife and the stock support said guides have proved unsatisfactory. It seems advantageous, therefore, to provide

means whereby some associated part of the knife carriage may serve the purpose of a guide for placing the stock. This may be accomplished by providing means for causing the knife carriage to move in a closed path together with means for varying the in ⁵ tiai position of said carriage and thereby the position at which it comes to rest. In order to cause the knife carriage to move in a closed path and to allow the initial position of said carriage to be varied at will, said carriage may be operated from a rotating member by a link or other rigid connecting means, the end remote from said carriage being adjustable in a segmental path struck about the axis of rotation of said rotating member, the machine being provided further with means for causing the rotating member to come to rest always at ¹⁰ a fixed point. By this arrangement the knife carriage or some associated part thereof may serve as a stop against which the edge of the stock may be held preparatory to the splitting operation, the knife carrying member or one of its associated parts thus serving as an adjustable guide which can be set so as to produce in the stock a slit, or to remove from said stock a shaving, as the case may be, of any desired length. ¹⁵

Another object of my invention relates to the provision of means for giving a curved or fancy contour to one edge of the shaving which is removed from the stock. By this means one edge of the shaving may be given any sort of curved outline or may be pinked in any design desired. In one embodiment this may be accomplished by providing the knife which slits the stock with the desired outline, in which case the gage will be provided with a corresponding outline. In another embodiment in which a second knife is used the edge of said second knife will be given the contour desired. ²⁰

These and other features of the invention including certain details of construction and combination of parts will be explained in connection with the following description of a machine and will be pointed out in the claims. ²⁵

As illustrating concrete examples of the uses to which the invention may be put the machine may be used to form a flap extending from the back of the heel of a sole to the shank so that said flap may be bent down in front of the breast of a wooden heel such as is used on certain varieties of slippers and thereby constitute a portion of the leather covering of the heel. Or the machine may be used to remove from stock a portion which is not needed in the use to be made of the stock, and which may be capable of other use. For instance, it may be used to cut a shaving from the grain side of the heel of a died out innersole, and after the shoe has been assembled the shaving, which may have ³⁰ been rolled and died out in the meantime, may, if desired, be cemented back in place to cover the clenched ends of the nails that pass through the heel of the sole, thus saving the expense of providing a separate lining or innersole to cover sail nails. Again, in providing shoes with cushion heels, the machine may be used to slit the heel of the innersole preparatory to inserting the cushion. Various other uses for the device will ³⁵ occur to those familiar with the art. ⁷⁰

Referring to the accompanying drawings, Figure 1 is a perspective view of a machine embodying my invention; Fig. 2 is a longitudinal section thereof; Fig. 3 is a sectional view of a portion of the machine showing the presser gage in operative position, the knife having just removed a shaving from the stock; Fig. 4 is a sectional view in every respect similar to Fig. 3 except that the presser gage is shown in inoperative position; Fig. 5 is a perspective view of a modified machine; Fig. 6 is a broken longitudinal section thereof; Fig. 7 is a detail showing a knife and bed which are suitable for use with either of the machines shown; and Fig. 8 is a detail of another modification. ⁸⁰

Referring to Figs. 1 to 4 the machine comprises a base 2 having means such as bolt holes 3 by which to fasten it to a suitable support, and provided with ways 4 for a carriage 6 which may be reciprocated on said ways by means of a connecting rod 5 which in turn may be operated by mechanism presently to be described. On base 2 is mounted a work bed or support 14. In the embodiment illustrated in Figs. 1 to 4 a corrugated plate 15 forms the upper part of this support or bed and is attached thereto by screws 19 so that it may be reversed end for end when desired, for a purpose hereinafter explained. It should be understood, however, that the plate might be made an integral part of the support and that instead of corrugations a plurality of pins or other equivalent holding means might be provided, such a construction being shown at 114 in Fig. 5. The bed 14 is supported over base 2 by springs 16, adjustable stops 18 being provided to limit the upward movement, but permitting said bed to yield against the tension of said springs. On carriage 6 is mounted the knife 20 in any approved manner, but preferably so as to be adjustable to compensate for wear. For instance, the knife may be mounted on the carriage 6 by means of bolts headed on their under ends so as to exert an upward pull on the knife and with their upper threaded ends passing through slots 17 and carrying nuts 27. In bearings 29 in the carriage and in advance of the knife is mounted a work clamping bar or gage 24 having trunnions or pivots 22 fitting in said bearings 29. The function of said gage is to engage the stock ⁹⁰ ⁹⁵ ¹⁰⁰ ¹⁰⁵ ¹¹⁰ ¹¹⁵ ¹²⁰ ¹²⁵ ¹³⁰

in advance of the knife and determine the thickness of the piece split off, it being evident that the yielding bed will take care of any unevenness in the stock so that said unevenness will not affect the thickness of the piece split off, the thickness being controlled entirely by the position of the gage.

It is advantageous to use a knife having a short bevel, since otherwise the cutting portion is greatly weakened and rendered liable to spring and cut a shaving of variable thickness, and in order to make possible the use of a knife having a short bevel it is desirable that that side of the gage which is in proximity to the knife shall rise abruptly from the stock. In addition, the gage should be of such form that it will readily ride up to the stock as the carriage is reciprocated. Accordingly this gage may be formed as a mutilated cylinder having its working face 31 curved or inclined from the bed in the direction in which the knife moves during its cutting stroke. By this formation both of the results indicated above as advantageous are secured, viz: a knife having a short bevel may be used, and the gage will readily ride up on to the stock.

In order to adjust the position of the gage 24 and hence regulate the distance below the surface of the stock at which the knife shall cut, means is provided for causing the gage to move the stock to different desired positions with respect to the knife. This means may conveniently be a pin 33 inserted in the gage and extending through a slot 35 in the carriage 6, said slot being sufficiently wide to allow the desired movement of the pin, it being evident that the farther the pin 33 is rotated toward the left (in Figs. 2, 3, and 4), the thinner will be the piece of stock split off. Any convenient means for holding the pin 33 in adjusted position may be employed. For instance a spring 37 may hold the pin against an adjustable abutment 39, which is in turn held by a set screw 41. It will be seen that by yieldingly holding the pin in adjusted position the gage may, by suitable means, be readily moved even during the operation of the machine to cause the knife to leave the stock. It should be understood, however, that said yielding holding means is not essential when the machine is used merely to produce on the stock a flap of uniform thickness, and is shown in the present embodiment merely because the illustrated machine is provided with means, the use of which is optional, for causing the flap produced on the stock to be removed therefrom. This latter means may be a gage presser 30 having a tongue which fits in a groove in the extended end of the connecting rod 5 and is held in position by a screw bolt 43, this connection permitting the position of the gage presser 30 to be reversed according as it is desired merely to produce

a flap of uniform thickness or to separate from the stock the flap thus produced, the two positions of the gage presser 30 being shown in Figs. 4 and 3. The gage presser is attached to an extension 45 of the connecting rod 5. This rod is pivoted at 47 to the carriage 6, and, as the opposite end of the connecting rod is caused to describe a circle, by mechanism presently to be described, the gage presser 30 describes an arc about the pivot 47 as a center and wipes across a roller 49 mounted on the pin 33 thereby depressing the gage and causing the knife to emerge from the surface of the stock.

Although the gage presser has been shown as having a plane working face and operating to move the pin 33 in one direction only it should be understood that the form of said gage presser may be varied if desired.

In machines of this class wherein the knife during its cutting stroke moves always to a fixed position the length of the slit produced in the stock, or of the shaving removed therefrom, as the case may be depends upon the position at which the stock is applied by the operator to the bed. In order to facilitate rapidity and accuracy in placing the stock attempts have been made to provide upon the bed adjustable stops or projections against which the stock could be held until the gage rode over its edge and pressed it firmly against the table, but the use of such stops has been extremely unsatisfactory owing to the small amount of space available, it being understood that the stop must not extend up into the path of the knife or gage.

In the preferred embodiment of the machine means for reciprocating the carriage is provided whereby the use of stops or projections on the bed is done away with. This means acts in such a manner that the movements of the carriage may be made periodic and that the carriage may be caused to begin its movement from any given position with respect to the bed and to end its movement at the same position. Consequently the gage itself acts as a stop against which the operator may place the edge of the stock and inasmuch as each periodic movement of the carriage takes the carriage over its whole path, the stock is always uncovered after being split so that it may easily be removed. Any suitable means for reciprocating the carriage and for causing it to begin and end its movement at any given point in its path may be employed. In the illustrated embodiment a connecting rod 5 is pivoted to the carriage at 47 and is pivotally attached to a rotatable plate 51 by means of a pin 53 which is adjustable in the segmental channel 55, said channel being undercut as shown so that the sleeve which surrounds pin 53 and which serves as a bearing for the eye 57 of the connecting rod 5 may be clamped in

any desired position in the segmental channel by means of the nut 54. The segmental channel 55 is struck about the axis of rotation of the plate 51 as a center, and consequently the carriage is caused to move in a fixed closed path regardless of the point at which motion begins. And if the plate 51 is caused always to start from and stop at one fixed position, the carriage 6 will be caused similarly to start from and stop at any desired position with regard to the bed 14 merely by changing the adjustment of the pin 53. Accordingly means are provided for causing the desired movement of the plate 51, said means comprising in the illustrated form a plurality of parts which will now be described.

The plate 51 has a spindle 59 which is mounted in a bearing 61; about the upper part of this bearing is mounted a rotatable sleeve 63 carrying a gear wheel 65, which is rotated by a worm 67 on a shaft 69, which carries fast and loose pulleys 71 and 73. In the upper part of the sleeve 63 are formed a series of notches 75 which are adapted to receive a latch 77 pivoted in a slot in the plate 51 and continually acted upon by a spring 79 which tends to press said latch into position to be received by one of the notches 75. With the construction thus far described, if the sleeve 63 were rotated the latch 77 would be forced into one of the notches 75, and the plate 51 would rotate continuously. In order to control the rotation of plate 51 a bell crank lever 81 having an extension 83 to which is attached a latch raising member 85 is mounted on a rock shaft 87. This bell crank lever is held in the position shown in full lines—in which position the latch 77 is raised and the plate 51 at rest—by a spring 89, and is moved to the position shown in dotted lines by depressing the treadle 91, in which position the latch 77 is forced by the spring 79 into one of the notches 75 in the rotating sleeve 63. In order to insure the stoppage of the plate 51 at exactly the same position always, the bell crank lever 81 has a second extension to which is attached a block 92 having a slot 93 with which a pin 94, fast to the plate, engages. One wall of the slot is beveled as at 95, and the momentum of the plate causes the pin to ride up the bevel thus depressing the block slightly until the pin arrives opposite the slot when the spring 89 causes the two to engage, thereby locking the plate 51 against movement and causing it to come to rest always in the same position.

In order to facilitate the setting of the carriage at the desired initial position so that a cut of the desired length may be produced, the bed 14 may be provided with a scale 96. And this scale is also useful in case a high degree of accuracy is not required and the machine is run continuously.

In such case the operator determines the length of the cut by placing the edge of the stock in proper position on the scale.

The operation of the device is as follows: By means of the adjustable pivot pin 53 and its associated parts the eye 57 of the connecting rod 5 is fixed at any desired position on the segmental channel 55. This determines the initial position of the carriage 6 and hence the length of the cut 75 which will be produced in the stock. The stock is then laid on the bed with its edge against the gage 24 and the treadle 91 depressed. This allows the spring 79 to depress the latch 77, which is engaged by one of the notches 75 of the sleeve 63, it being understood that this sleeve is constantly rotated while the machine is being used. The treadle 91 is then released to allow the spring 89 to return the bell crank lever 81 85 to its initial position. The plate 51, being thus connected with the sleeve 63, revolves in the direction of the arrow in Fig. 1. This causes the carriage 6 first to accomplish its cutting stroke then to withdraw to its extreme opposite position, thereby uncovering the stock, and then to return to its initial position. Just before the carriage reaches this position the member 85 raises the latch thereby disconnecting the plate 51 from the sleeve 63, and then the pin 94 rides up the bevel 95 and engages the slot 93. At this instant the carriage 6 comes to rest exactly in its adjusted position and ready to make another cut of exactly the same length as 95 the first one.

When it is desired to cut a shaving from the stock the gage presser 30 is set as shown in Fig. 3 so that, as the connecting rod 5 moves in its path, the extension 45 will cause 105 the gage presser 30 to describe the arc of a circle and in doing so to wipe across the roller 49, thereby depressing the gage to cause the knife to leave the stock, and to cut from said stock a shaving of uniform 110 thickness and having a beveled edge at the end last cut. On the other hand when it is desired merely to split or slit the stock the gage presser 30 is set as shown in Fig. 4 so that it cannot contact with the roller 49. 115

It will be noticed that the plate 15 of the bed is shown in one position in Fig. 3 and in reversed position in Fig. 4. In Fig. 3 a shaving 97 is being removed from the flesh side of a sole. In this case the cut is a light 120 one and consequently it is unnecessary that a large area of the under side of the sole should be engaged by the corrugations of the plate. Moreover, it is very undesirable to disfigure the grain side any more than is necessary, and therefore the plate is so placed that the knife overruns the corrugations. In Fig. 4, on the other hand, a slit is being produced in the grain side of a sole. Here the cut is a heavier one and hence it 125 130

is necessary that more of the corrugations shall engage the sole. In this case the flesh side is the under one and there is no special reason for preserving it from the disfigurement caused by the corrugations.

Referring now to Figs. 5 and 6 the base 102 together with the ways 104 and the yielding bed 114, supported by means of the springs 116, and the adjustable stops 118 are similar to the corresponding parts of the preferred embodiment. A gage 124 of different form pivoted at 122 is held in its highest position by a spring 26 which is interposed between the carriage 106 and the lip 25 the position of said gage being determined by the contact of the upper inclined surface of said gage with a part of the carriage 106 against which it seats. A toggle link 8, that is pivoted to carriage 106, carries by means of an adjusting screw 28 a gage presser 130 which may engage lip 25 of the gage 124 when the toggle has reached a certain point in its movement and depress the gage as the movement of the toggle continues, the further operation of the parts being similar to the corresponding parts in the preferred embodiment. The knife 120 may be mounted on a knife carrying member 19 in such a way as to be adjustable to compensate for wear; and this member 19 may be secured to carriage 106 by set screws 23, adjusting screws 121 being provided to adjust the position in which the member is supported on said bed and consequently to determine the inclination of the knife and the thickness of the piece split off.

The carriage 106 is reciprocated manually by means of a treadle 10 connected to toggle links 8, a spring 12 being provided to effect the return of the treadle and with it that of the carriage, the return movement of said carriage being limited by the stop 13. This modified machine, it will be observed, differs from the preferred form in general by the fact that no means is provided for causing the carriage to come to rest at any desired point.

In Fig. 7 is shown a knife adapted for use with either form of machine described above and having a curved edge so as to give a fancy contour to the edge of the piece separated from the stock it being understood that the outline of the edge of the knife may be varied as desired and that with any given outline the operative edge of the gage will be formed correspondingly.

Referring now to Fig. 8, the frame 2, carriage 6, support 14 and associated plate 15, springs 16, screw bolts 18, pivot 47 and gage 24 are of the same form as those shown in Figs. 1 to 4 inclusive. The connecting rod 205, however, has no extension; and no automatic means for causing the gage to depress the stock is shown. In order to cause the flap 98 produced on the stock to be removed

therefrom if desired, a member 202 is mounted on a rock-shaft 204, said shaft being journaled on the carriage and said member being held in any desired angular relation with respect to said rock-shaft by any suitable means as, for example, a set screw 210. To this member a knife 206 is adjustably attached by means of a set screw 208 which passes through a slot in said knife. In order to cause this knife to become operative a lever 212 depends from the rock-shaft, in the illustrated form being shown as integral with it, said lever being engaged on the return stroke of the carriage by an adjustable abutment 214 which is adapted to be held in adjusted position on the frame 2 by a set screw 216 which passes through a slot in said abutment or by any suitable means. As a means for adjusting the gage 24 and thereby the distance below the surface of the stock at which the knife 20 operates, a screw 233 enters a socket in said gage and bears against a collar 235, so that by advancing the screw said screw is securely held in any desired position in the slot 35, and consequently the gage is similarly held with respect to the carriage 6. It should be understood that this particular means for adjusting the gage is not essential and that any other suitable means as, for example, that shown in Figs. 1 to 4 inclusive might be substituted. The operation of this form is similar to that of those previously described. The gage 24 having been adjusted and the carriage withdrawn so as to expose part of the bed, a piece of stock is laid on said bed and the carriage 6 reciprocated. The knife 20 will thus, during the forward stroke produce a flap of uniform thickness on the stock, the lever 212 riding over the abutment 214 without causing the knife 206 to operate. On the return stroke the lever will again engage the abutment, this time causing the knife 206 to enter the stock and remove therefrom the flap or shaving produced by the knife 20. By means of the set screw 208 the depth to which the knife 206 shall enter the stock may be regulated, while the set screw 210 affords means for varying the point at which the knife begins to operate and the angle at which it cuts. It should be noticed that by removing the abutment 214 or by adjusting the set screws 208, 210 the knife 206 may be rendered inoperative. It should be understood also that the contour of the cutting edge of the knife 206 may be varied, if desired, so as to produce a curved or fancy outline on one edge of the shaving removed from the stock.

Although the machine has been described as having a movable knife and a fixed stock support, it should be understood that relative motion between the two is all that is essential; and although the motion has been

described as reciprocation, it should be understood that the motion might take place in any other suitable path.

The invention has been set forth in connection with a specific machine. The machine, however, is purely illustrative and nothing herein contained is to be construed as limiting this invention in the scope of its application to the specific machine shown and described.

Having described the invention and the method of operation what is claimed and desired to be secured by Letters Patent is:—

1. A machine of the class described, having, in combination, a knife, a carrier therefor, a stock support over which said carrier is movable, a rotatable member for actuating said carrier, mechanism for causing said member to make one revolution and come to rest, a connecting rod, pivots connecting said rod at one end with said carrier and at the other end with said rotatable member, and means for clamping one of said pivots in different adjusted positions.

2. A machine of the class described, having, in combination, a bed for supporting a piece of stock, the location of said stock upon said bed being maintained fixed throughout the operation of the machine, a knife, means for causing relative movement between said knife and bed to produce a flap on said stock, and automatic means operated by said relative movement for causing said flap to be removed.

3. A machine of the class described having, in combination, a bed for supporting a piece of stock, the location of said stock upon said bed being maintained fixed throughout the operation of the machine, a knife, means for causing relative movement between said knife and bed to produce a flap on said stock, a gage located in advance of said knife, and automatic means operated by said relative movement for moving said gage toward said bed.

4. A machine of the class described, having in combination, a yielding support for stock, means, including a knife and a gage movable in unison, to produce a flap on stock so supported, and automatic means for causing said flap to be separated from said stock.

5. A machine of the class described, having in combination, a substantially flat bed for supporting stock, means acting to produce a flap on stock so supported, means for causing said flap to be separated from said stock at a given point, and means for varying that point.

6. A machine of the class described, having in combination, a substantially flat bed for supporting stock in position to be acted upon, and means acting to remove from stock so supported a shaving of substantially uniform thickness, having one edge beveled and of curved outline.

7. A machine of the class described, having in combination, a substantially flat bed for supporting stock in position to be acted upon, and means acting to remove from stock so supported a shaving of substantially uniform thickness, and having the edge last separated from the stock beveled.

8. A machine of the class described, having in combination, a substantially flat bed for supporting stock in position to be acted upon, and means acting to remove from stock so supported a shaving of substantially uniform thickness, and having an edge of curved outline.

9. A machine of the class described, having in combination, a bed for supporting stock, a knife movable relatively to said bed to split the stock for a given distance, a gage co-acting with said knife to determine the thickness of the flap resulting from said splitting of the stock, and means becoming operative at a predetermined point in the movement of the knife to separate said flap from the remainder of the stock.

10. A machine of the class described, having in combination, substantially flat stock supporting means, a knife, a gage co-acting therewith to determine the thickness of the piece split by the knife, and means acting on said gage to vary said thickness during the operation of the machine.

11. A machine of the class described, having in combination, substantially flat stock supporting means, a knife, a gage co-acting with said knife to determine the thickness of the piece split by said knife, and means acting on said gage to cause said knife to leave the stock.

12. A machine of the class described, having in combination, substantially flat stock supporting means, a knife, a gage co-acting therewith to determine the thickness of the piece split off, means acting on said gage to cause the knife to leave the stock, and means for adjusting the machine to change the point at which said knife leaves the stock.

13. A machine of the class described, having in combination, a substantially flat yielding bed for supporting the stock, a knife, a pivoted gage co-acting with said knife, and means acting to turn said gage on its pivot to vary the thickness of the piece cut.

14. A machine of the class described, having in combination, substantially flat stock supporting means, a knife, a gage co-acting therewith, means moving said knife and supporting means relatively to split the stock, and means becoming operative when said knife has moved a certain distance relatively to said supporting means to cause said knife to leave the stock.

15. A machine of the class described, having in combination, substantially flat stock supporting means, a knife, a gage co-acting therewith, means moving said knife and

- bed relatively to split the stock, means becoming operative when said knife has moved a certain distance relatively to said bed to cause said knife to leave the stock, and means for determining the point at which said last mentioned means becomes operative.
16. A machine of the class described, having in combination, a substantially flat bed for supporting stock, a knife movable relatively to said bed to split the stock, and means for moving the stock out of the path of the knife to determine the amount of stock split off.
- 15 17. A machine of the class described, having in combination, a substantially flat bed yieldingly supported, a splitting knife movable with relation to the bed to split stock supported by the bed, and means for de- 20 pressing the stock supported on the bed to cause the knife to leave the stock.
18. A machine of the class described, having in combination, a yielding bed to support stock, a knife movable relatively to said bed to split stock supported upon it, and a gage located in advance of the knife and movable with it to determine the depth of cut and also movable transversely of the path of the knife to depress the stock out of 30 the path of the knife.
19. A machine of the class described, having in combination, a stock supporting bed, a knife, a gage co-acting with said knife to determine the thickness of the piece split 35 from the stock, means for moving said knife and gage together over the bed to split stock, and means acting to vary the relation of said knife and gage to vary the thickness of the piece split.
- 40 20. A machine of the class described, having in combination, substantially flat stock supporting means, a knife, a gage co-acting therewith to determine the thickness of the piece split by the knife, and means acting to move said gage and knife relatively during 45 the operation of the machine to vary the thickness of the piece split.
21. A machine of the class described, having in combination, a substantially flat stock support and a cutting member, said support and member being capable of relative movement lengthwise of the support to cut the work, and means for causing said support and member to come to rest in different relative positions.
- 50 22. A machine of the class described, having in combination, a cutting member and a substantially flat support, means for moving one of said members lengthwise of the other, and means for causing said movable member to come to rest at different desired points.
- 55 23. A machine of the class described, having in combination, a bed for supporting stock, means movable in a path of uniform length over said bed and acting to split stock
- supported thereby, and means for determining the point at which said movable splitting means starts and comes to rest.
24. A machine of the class described, having in combination, a bed for supporting stock, means acting to split stock so supported, means to cause said splitting means to start and come to rest at a given point and means for varying that point.
- 70 25. A machine of the class described, having in combination, a yielding support, splitting means, including a knife and a gage, reciprocating over said support in a path of uniform length, and means for varying the point at which said reciprocation begins and ends.
- 75 26. A machine of the class described, having in combination, a support, a knife movable relatively to said support, one of said parts being yieldable, and an adjustable gage located in advance of the knife and movable with it to determine the location of the cut.
27. A machine of the class described, having in combination, yielding means for supporting stock in position to be acted upon, means acting to split stock so supported, and means for varying the effective stroke of said splitting means.
- 80 28. A machine of the class described having, in combination, a stock supporting member, a knife and gage supporting member movable in a fixed path over said stock supporting member, mechanism for actuating said members relatively, and selective means connected with said actuating mechanism for determining in what portion of said path said knife shall be effective.
- 85 29. A machine of the class described, having in combination, a yielding bed for supporting stock, a knife movable with respect to said bed, a gage moving with said knife and acting to depress stock supported on said bed, means for causing said knife and gage to start and come to rest at a given point and means for varying that point.
- 90 105 30. A machine of the class described, having in combination, a supporting bed, a carriage movable over said bed, one of said parts being yieldable, a knife, and a gage mounted in said carriage, means for moving said carriage and means for determining the point at which said motion begins and ends.
- 110 31. A machine of the class described, having in combination, a yielding bed for supporting stock, a knife movable over said bed, a gage movable in advance of the knife, and means for varying the point at which said knife and gage come to rest, whereby the gage may serve as an adjustable stop against which to present the stock.
- 115 32. A machine of the class described, having in combination, a bed for supporting stock, a knife movable with respect to said bed, a gage moving with said knife and act-
- 120 125 130

- ing to depress stock supported on said bed, means for causing said knife and gage to start and come to rest at a given point, and means for varying that point.
- 5 33. A machine of the class described, having in combination, a support for stock, a knife and a gage movable in unison relatively to said support, means for producing relative movement between the support and 10 the knife and gage, and means for varying the relative point at which said motion ceases.
34. A machine of the class described having, in combination, substantially flat stock 15 supporting means, a knife, a gage co-acting therewith to determine the thickness of the piece split by the knife and means for varying said thickness during the operation of the machine.
- 20 35. A machine of the class described having, in combination, a bed for supporting stock, a knife movable relatively with respect to said bed to split the stock and a gage located a fixed distance in front of the 25 edge of the knife, said gage and bed being relatively movable toward each other during the operation of the machine, and automatic means for producing such movement.
36. A machine of the class described having, in combination, a bed for supporting stock, a knife and gage for acting upon stock so supported, means for producing relative movement between said bed and said knife and gage, and means for varying the relative position in which said bed and said 35 knife and gage come to rest.
37. A machine of the class described having, in combination, a substantially flat supporting bed, a knife, means for producing relative movement between said bed and 40 knife, and a gage located in advance of said knife, said gage being of the form of a mutilated cylinder.
38. A machine of the class described having, in combination, a bed for supporting 45 stock, a knife movable relatively to said bed to split said stock for a given distance, a gage co-acting with said knife to determine the thickness of the flap produced, a moving member, a gage presser carried thereby, and 50 means whereby said gage presser may be held in operative or inoperative position at will.
39. A machine of the class described having, in combination, a bed for supporting a 55 piece of stock, a knife, means for causing relative movement between said knife and bed longitudinally of said bed, yielding means for permitting relative movement between said knife and bed in a direction at 60 an angle to the plane of said bed, and automatic means operated by said first named movement for causing said last named movement.
- In testimony whereof I have signed my 65 name to this specification in the presence of two subscribing witnesses.
- FREDERICK M. FURBER.
- Witnesses:
- FRED W. GUIBORD,
FREDERICK L. EDMANDS.
